DESIGN FOR A RESTAURANT BOOTH

Richard Sisco, Clifton, N. J.

Application December 5, 1935, Serial No. 59,917

Term of patent 14 years

To all whom it may concern:

Be it known that I, Richard Sisco, a citizen of the United States and a resident of Clifton, in the county of Passaic and State of New Jersey, have invented a new, original, and ornamental Design for a Restaurant Booth, of which the following is a specification, reference being had to the accompanying drawing, forming part thereof.

I claim:

The ornamental design for a restaurant booth as shown and described.

RICHARD SISCO.
